Specification of Letters Patent.

Patented Feb. 5, 1918.

Application filed January 4, 1915. Serial No. 393.

To all whom it may concern:

Be it known that I, MALCOLM F. EWEN, a citizen of the United States, and a resident of Chicago, in the county of Cook and State of Illinois, have invented certain new and useful Improvements in Refrigerating Apparatus; and I do hereby declare that the following is a full, clear, and exact description thereof, reference being had to the accompanying drawings, and to the letters of reference marked thereon, which form a part of this specification.

This invention relates to improvements in refrigerating apparatus and consists of the matters hereinafter described and more particularly pointed out in the appended claims. The invention relates to a refrigerating apparatus of the absorption type which includes in general a generator or still, an absorber, a liquid refrigerant receiver and an expansion chamber or coil, and in addition includes an expansion or conducting valve interposed between the liquid receiver and the expansion chamber for controlling the admission of liquid refrigerant thereto.

The improved apparatus is more particularly of the kind known as a continuously operating apparatus in which the generator or still and the absorber are always used respectively as a still and as an absorber and are continuously subjected, in the normal operation of the apparatus, the one to heat and the other to the action of a cooling agent.

A pump is employed to withdraw the liquor saturated with the refrigerant from the absorber and force it into the still, and the pressure generated in the still is made use of to force the desaturated weak liquor from the still to the absorber.

No claim is made herein to a refrigerating apparatus embodying the several features above referred to, but the invention lies in the combination of certain improved features with the other elements of such an apparatus whereby such an apparatus is made commercially practicable and efficient. These several features, as well as the various advantages of the improved refrigerating apparatus, will appear more fully as I proceed with my specification.

In the drawings:

Figure 1 illustrates a view in front elevation of a refrigerating apparatus made in accordance with my invention, a part of said

view being shown in section to more clearly illustrate the interior construction thereof.

Fig. 2 illustrates a top plan view of the same.

Fig. 3 illustrates a view in end elevation 60 of my improved refrigerating apparatus as viewed from the right hand end of Fig. 1.

Fig. 4 illustrates a transverse vertical section through my improved refrigerating apparatus, the plane of the section being indicated by the line 4-4 of Fig. 1.

Fig. 5 illustrates a longitudinal vertical sectional view through the apparatus, the plane of the section being indicated by the line 5-5 of Fig. 2.

Fig. 6 illustrates a longitudinal vertical section on an enlarged scale through the upper end of the absorber.

Fig. 7 is a detail sectional view on an enlarged scale of a valve interposed in the connection between the condenser and the expansion coil of the apparatus.

Fig. 8 illustrates on an enlarged scale a detail vertical sectional view, the plane of the section being indicated by the line 8-8 80 of Fig. 1.

The apparatus illustrated herein as an embodiment of my invention is designed more particularly for the use of ammonia as the refrigerant and water for the absorbent, and hereinafter without further explanation, I shall so describe it, but it will be understood that the apparatus and improved features are not necessarily limited to the use of such refrigerant and such absorbent.

Referring now to that embodiment of my invention illustrated in the drawings and particularly to Figs. 1 and 2:-10 indicates the generator or still, 11 indicates the absorber, 12 indicates the liquid refrigerant receiver, 13 indicates the pipe leading from the condenser to the expansion chamber or coil (13^x) and 14 the return pipe leading from the said expansion chamber or coil back to the absorber and adapted to return the vaporized expanded refrigerant, ammonia, to the absorber, wherein it is taken up by the liquor, water. The admission of the refrigerant through the pipe 13 leading to the expansion coil or chamber is controlled 105 by a valve mechanism 15 which is operated automatically and periodically in a manner later to be described.

Any convenient means may be used for heating the still or generator 10, and I have 110

illustrated herein that most usually used and most conveniently at hand in the localities where refrigeration of the kind herein described is apt to be used, that is to say, a 5 gas burner. 16 indicates the burner which consists of a long pipe provided with suitable orifices for the escape of the gas and extending longitudinally below the still which as shown is in the form of an elongated 10 drum. The still 10 is surrounded at the top sides and ends by means of a heat insulating jacket 17 which may be of any suitable or desirable construction. A stack 18 is connected with the jacket intermediate its ends 15 for the escape of the products of combustion. The burner is supplied by a pipe 19 which is connected with any suitable source of gas supply. The burner is intended to burn all the time that the apparatus is in 20 operation and therefore may be controlled by any suitable hand valve or cock (not shown). The supply pipe, however, is in addition provided with an automatic valve 20 for cutting off the supply of gas under 25 certain circumstances to be more fully described later.

The absorber 11 and the condenser-receiver 12 are preferably made as illustrated in the form of upright elongated cylindric 30 shells closed at top and bottom. Said shells are supported in any convenient way in an upright tank 21 adapted for containing cooling water. Said tank is preferably made of sheet metal and is supported as shown 35 on end brackets or frames 22-22 which somewhat elevate the said tank above the floor upon which the apparatus is located. The still 10 is supported from the front wall of the tank 21 by means of suitable brackets 40-23.

The still 10 is connected to the condenser-receiver 12 by means of spaced pipes 24-24 which rise a short distance above the still and are then carried back through the front 45 wall of the tank 21 and then upwardly to a point within the tank where they are joined together and to a common discharge pipe 25 which enters the condenser-receiver tank 12 at the top. The pipes 24-24 constitute a rectifier of familiar construction 50 which is cooled by the water within the tank 21 so that the water carried from the still with the ammonia gas is condensed therein and directed back into the still.

55 The absorber 11 is connected with the still by means of a pipe 26 which is connected at one end, namely, the end 26^a, to the bottom of the absorber and at the other end, namely, the end 26^b, to the bottom of the 60 still at one end. Said pipe preferably includes a branch 26^c which is conducted horizontally above the still in the air jacket space between said still and the heat insulating shield 17 in order to preliminarily 65 heat the saturated strong liquor before it

enters the still. A pump 27 (see Fig. 1) is interposed in the pipe 26 and is adapted to withdraw the saturated strong liquor from the bottom of the absorber and force it into the bottom of the still. The pump is 70 preferably a double-acting reciprocating piston pump of any familiar well-known type, and as shown is operated by a water motor indicated at 28. The water motor 28 is connected by a pipe 29 which supplies it with water at the usual city pressure, the flow being controlled by a valve 30. The pump and the motor are slow acting and are arranged so as to withdraw periodically and continuously a small amount of saturated strong liquor from the absorber and force it into the still with each stroke of the pump. 75

The weak liquor is discharged in a familiar manner from the still into the absorber 85 under the pressure within the still through a pipe 31 which has one end 31^a connected to the bottom of the still at a point opposite and farthest removed from the end 26^b of the strong liquor pipe 26, and has its other 90 end 31^b opening into the top of the absorber 11. Said end 31^b is preferably provided with a discharge spray ring 32 by means of which the weak liquor is discharged in the form of rain through the ammonia gas in 95 the top of the absorber, so that it will rapidly and quickly absorb said gas. In the pipe 31 is preferably interposed a cooling coil 33 which extends upwardly through a space 34 in the front of the tank 21 which 10 is divided from the rest of the tank by means of an upright partition wall 35. Said partition wall is closed at its ends against the end walls of the tank 21 and extends substantially to the top of said tank 10 but is terminated a short distance from the bottom of the tank to form a communicating passageway 36 between the front compartment of the tank in which the said cooling coil is located and the rear compartment of 11 the tank in which are located the absorber and receiver. By this arrangement the water which is apt to be more highly heated on account of the temperature of the hot weak liquor, is prevented from coming into 11 direct contact with the condenser-receiver and absorber.

The flow of weak liquor to the absorber is controlled by an automatic valve 37. Said valve as shown consists of a casing in the 12 form of a T-joint 38; of an apertured valve seat 39 fixed in one end of the cross of T-joint and of a vertically reciprocating valve needle or stem 40, which has guiding relation within a vertical passageway in a plug 12 41 fixed in the other end of the cross of the T. The valve is operated by a lever 42 having a fulcrum 43 located close to the valve stem 40 and mounted within a horizontal pipe 44 which connects the T casing 13

38 with a T-joint 45 which is directly connected to the discharge end 31^b of the pipe 31. The lower end of said pipe end 31^b is closed by means of an apertured plug 46 which provides guiding engagement and supports a vertically reciprocating rod 47 that is operatively connected to the lever 42 by a pivotal joint 48. The rod 47 is provided at the bottom with a ball float 49. 10 The ball float 49 in connection with the lever 42 and valve mechanism 37 operates to control the admission of the weak liquor into the absorber in such manner as to maintain a pre-determined amount of liquid in 15 the absorber. Manifestly as the float rises the lever will be operated to choke or close the valve opening through which the weak liquor is supplied to the absorber and as 20 said ball float descends said opening will be opened or enlarged. The pipe 14 which leads the vaporized expanded refrigerant from the expansion chamber or coil to the absorber has a branch 14^a which is conducted to the bottom of the absorber where it has 25 attached to it a discharge ring 14^b by means of which the ammonia gas is discharged at the bottom of the absorber so as to rise therein.

The cooling water for the apparatus is 30 supplied by the exhaust of the water motor 28 which drives the pump 27. As illustrated said exhaust is conducted by a pipe 50 up through branch pipes 51—51^a to coils 52—52^a rising vertically in the absorber and condenser-receiver respectively. The upper 35 ends 53—53^a of said coils open through the tops of their respective shells and the overflow from said coils fills the tank 21. The tank itself is provided with an overflow pipe 40 54 which communicates with the front compartment 34 of said tank so as to discharge from the tank the hotter water. Said pipe is connected in any convenient manner with the sewer (not shown).

45 As it sometimes happens that the supply of water may be unexpectedly cut down or completely shut off, I provide means whereby the apparatus may be stopped and the gas supply cut off under such circumstances. This is particularly important since the continuous heating of the still without a supply 50 of cooling water to dissipate and get rid of the heat might result in dangerous conditions. This means as shown is as follows:

55 indicates a float in the top of the tank 21 fixed to the end of a lever 56 which is fulcrumed at 57 to the top of the tank. Said lever has an arm 58 which carries a cam 59 and a cam 60. The valves 20 and 30 are operated by spring controlled plungers 20^a 60 and 30^a respectively, which are so arranged that they normally hold the valves open. The cams 59 and 60 are arranged to coact with said plungers in such manner that when the float 55, owing to the fall of the level of

the water in the tank 21, descends to a certain point, said cams will act to close the fuel gas supply valve 20 and the water supply valve 30.

The upward movement of the lever 56 is limited by means of a pin 61. 62 indicates a pivoted arm or trigger pivotally mounted on a rod 63 at the top of the tank and normally resting against the lever 56. The lever 56 has a notch 64 which is adapted to be engaged by the arm or trigger 62 when the lever in the descent of the float has reached a certain position, so that it will be locked in said position by said trigger; thus the valves 20 and 30 will both be locked and the further flow of fuel gas and water will be prevented until an attendant opens the valves.

In order that the water may fall to the predetermined required low level to operate the lever 56 as heretofore described after the 85 water supply has failed, the overflow pipe 54 for the tank 21 is provided with a supplemental by-pass 65, by means of which the water will flow into the pipe 54 and thus discharge the tank to the level required to 90 operate the float. Said by-pass 65 is made of smaller diameter than the main overflow connection with the discharge pipe 54 so that under normal conditions it will have little or no effect upon the discharge 95 of water from the tank. As hereinbefore pointed out the admission of the liquid ammonia to the expansion chamber is controlled by the valve 15. Said valve is a positively operated intermittently opened and closed 100 valve and differs from the usual reducing or expansion valve in that instead of providing for a continuous choked flow of the liquid ammonia through a restricted passageway to the expansion coil, it operates to admit at 105 periodic regular intervals, a larger flow of liquid ammonia through an unrestricted passageway for a short interval. The liquid ammonia is thus supplied continuously but intermittently and the disadvantages resulting from the use of expansion valves are thus entirely done away with.

The valve 15 comprises a casing 15^a which is divided by means of a transverse wall 15^b into an inlet chamber 70 and an outlet chamber 71. The partition wall 15 is provided with a comparatively large aperture 72 and said aperture is adapted to be closed by a conical valve plug 73 on the end of a valve stem 74. The valve stem 74 is reciprocably mounted in a suitable stuffing box 75 which closes the outlet chamber of the valve casing. The inlet end of the valve casing is closed by a plug 76. The inlet valve chamber is connected to the condenser-receiver side of the condensing pipe 13 and the outlet chamber to the expansion coil side of said pipe. A coiled expansion spring 77 surrounds the valve stem 74 and bears at one end against

the stuffing box 75 and at its other end against a washer 78 fixed on the upper end of the valve stem. This spring thus normally tends to hold the valve plug closed 5 against the aperture 72.

79 indicates a lever pivoted at 80 to the valve casing and pivotally connected at 81 to the valve stem 74. The other end of said lever is attached to a plate 82 (see Figs. 1, 10 2 and 8), which depends into the path of a lug 83 on the cross head 84 of the pump 27. The depending plate 82 and the lug are so shaped, the one with reference to the other, that when the lug 83 in its movement with 15 the reciprocating cross head strikes the plate 82 it will act to lift said plate each time it strikes it and with it the long arm of the lever 79 so as to depress the valve stem 74. Thus the lever 79 will be actuated to depress 20 the valve stem 74 twice during each complete reciprocation of the pump 27. As soon as the cross head passes the depending plate 82 the coil spring 77 will cause the valve to close and thus shut off the communication 25 between the inlet and outlet chambers of the valve casing 16. This spring is made very strong in its action so that the valve will be almost instantly closed after it is opened. The result is that the valve is completely opened twice for each reciprocation 30 of the pump but the open position is maintained for only a very short period. As the valve controlling the admission of liquid refrigerant to the expansion coil is positively 35 opened and positively closed in the manner described, it will be manifest to those familiar with the art that the improved apparatus is entirely free from those difficulties which occur where a reducing or expansion 40 valve is used and where the restricted openings necessarily used in connection with such valves are apt to be clogged by scale or other extraneous particles which may collect or be present in the apparatus or 45 where the movement of the valve itself in connection with the restricted opening may be interfered with and entirely prevented by the presence of such extraneous particles.

In order to positively cut off the admission 50 of liquid refrigerant to the expansion coil when the back pressure rises above a certain point, when it would prevent the efficient expansion and vaporization of the ammonia, I provide the following mechanism 55 in connection with the operating valve mechanism thus far described:

90 indicates a concavo-convex casing closed on one side by a thin sheet metal diaphragm 91 and connected on its other side opposite 60 to the said diaphragm by means of a pipe 92 to the absorber 11 in such manner that the pressure on the diaphragm will be equivalent to the pressure in the absorber. As long as the pressure in the absorber is such that

the vaporized, expanded ammonia gas will 65 be properly withdrawn from the expansion chamber, the mechanism now to be described will have no effect to influence the operation of the liquid ammonia admission valve 15. The heretofore referred to plate 82 70 which is operated upon by the lug 83 on the reciprocating cross head 84, is pivoted in such manner that it may be swung to one side so as to escape being struck by said lug. Said plate 82 is connected by a link 93 with 75 the diaphragm 91. Under the ordinary pressure the diaphragm will have no effect on the plate 82 but under a certain pressure which may be carefully pre-determined, the diaphragm will be forced to the left, as 80 viewed in Fig. 8, so as to swing the plate 82 out of the path of the lug 83 with the result that the reciprocation of the cross head would have no effect upon the lever 79 connected with the valve 73 and thus said valve 85 would remain closed under the action of the spring 77. Thus the liquid refrigerant would be no longer supplied to the expansion chamber and this condition of affairs would maintain until the pressure against 90 the diaphragm 91 was reduced which could only occur after the pressure in the absorber had been reduced, indicating that the ammonia gas flowing thereto from the expansion chamber was being properly absorbed 95 by the water therein.

A pivotal joint 93^a is made in the link connection between the swinging plate 82 and the diaphragm 91 so as to permit the up and down intended movement of said plate 82 in 100 the operation of the lever 79 under normal conditions.

The operation of my improved apparatus is apparent from the foregoing description. The strong liquor is drawn from the absorber by the pump into the still and the weak liquor is forced by the pressure in 105 the still from the still into the absorber.

The operation of the float 49 and the valve 37 controlled by said float acts to maintain 110 the proper pre-determined equilibrium between the amount of weak liquor in the absorber and the amount of liquor in the still under the varying conditions of operation of the pump due to variations of pressure 115 of water that operates the motor to drive the pump.

The liquid ammonia is admitted to the expansion chamber through a comparatively large unrestricted opening, at regular periodic intervals, so long as the conditions are such both in the apparatus itself and in the box or other chamber which is to be refrigerated, that no back pressure is accumulated 120 in the absorber to prevent the required efficient refrigeration by the ammonia in the expansion chamber. As soon as the said back pressure for any reason rises beyond 125

the proper predetermined point, the supply of liquid ammonia to the expansion chamber is absolutely cut off and remains cut off until normal conditions have returned.

5 In addition to this the ammonia admitted to the expansion chamber in the preferred form of the invention as illustrated herein, and under the normal operation of the apparatus without excessive back pressure beyond the predetermined point heretofore referred to, is controlled by the same means that controls the admission of the strong liquor to the still from which said liquid ammonia is generated. The ammonia supply in the two parts of the system being thus made to depend upon the same controlling device is therefore correlated so that the part taken from the condenser-receiver is substantially replaced by an equal amount 10 put into the receiver. The pump constitutes both a measuring device and a means for transferring the absorbent from the absorber to the still in certain timed relation with the operation of the valve connecting the still 15 with the expansion chamber. Thus an excess of ammonia may be provided in the system without any evil effects in its operation, even though the system is as has been shown practically valveless.

20 As the exhaust water from the motor is conveyed to the cooling water tank in which is contained the absorber and thus constitutes the means for renewing the cooling water and of maintaining the temperature 25 thereof, it will be apparent that this renewal of the water is correlated to the amounts of absorbent intermittently taken from the absorber and put into the still and the necessary temperature of the water will be therefore automatically maintained. Thus, when 30 the motor is operating rapidly the amount of cooling water required to cool the absorber will be automatically increased and when the pump moves more slowly this supply will be automatically decreased and the proper amount of fresh cooling water is maintained without waste, being supplied just as and no faster than it is required in the operation of the apparatus.

35 While the apparatus contemplates the constant burning of the fuel burner and the constant supplying of the cooling water, at the same time the means hereinbefore described for the control of both the fuel gas supply and the cooling water supply act to cut off the fuel gas supply upon the failure of the water supply. The failure of the gas supply of course would have no effect except to stop the operation of the apparatus 40 since the water would simply continue to be wasted to the sewer.

45 It will therefore be manifest that the apparatus is perfectly safe and may be operated without danger of any sort. In addition,

it will be noted that, except for the 65 positively acting valves referred to, the apparatus is valveless and is therefore immune from the many disadvantages of automatic refrigerating apparatus of the absorption type as heretofore manufactured. 70

While in describing my invention I have referred to certain details of mechanical construction and arrangement, it is understood that the invention is not in any way limited thereto, except as may be pointed 75 out in the appended claims.

I claim as my invention:

1. In a refrigerating apparatus of the kind described, in combination with a still, an absorber, a condenser-receiver connected with said still, a conduit connecting said still to said absorber, a conduit connecting said absorber with said still, a pump interposed in said second named conduit and means for operating the same, an expansion coil connected with said condenser-receiver 80 on one side and said absorber on the other, a positively operating valve interposed between said condenser-receiver and said expansion chamber, and means actuated by 85 said pump for opening said valve.

2. In a refrigerating apparatus of the kind described, in combination with a still, an absorber, a condenser-receiver connected with said still, a conduit connecting said still to said absorber, a conduit connecting said absorber with said still, a pump interposed in said second named conduit and means for operating the same, an expansion coil connected with said condenser-receiver 95 on one side and said absorber on the other, a positively operating valve interposed between said condenser-receiver and said expansion chamber, and means for periodically and automatically opening said valve. 100

3. In a refrigerating apparatus of the kind described, in combination with a still, an absorber, a condenser-receiver connected with said still, a conduit connecting said still to said absorber, a conduit connecting said absorber with said still, a pump interposed in said second named conduit and means for operating the same, an expansion coil connected with said condenser-receiver 110 on one side and said absorber on the other, a positively operating valve interposed between said condenser-receiver and said expansion chamber, means actuated by said pump for opening said valve, and means controlled by the pressure in said absorber 115 for disconnecting said pump mechanism from said valve mechanism when said back pressure exceeds a predetermined amount.

4. In a refrigerating apparatus of the kind described, in combination with a still, an absorber, a condenser-receiver connected with said still, a conduit connecting said still to said absorber, a conduit connecting

8
 said absorber with said still, a pump interposed in said second named conduit and means for operating the same, an expansion coil connected with said condenser-receiver

5 on one side and said absorber on the other, a positively operating valve interposed between said condenser-receiver and said expansion chamber, means for periodically and automatically opening said valve, and means
 10 for suspending the operation of said automatic valve opening mechanism when and while the back pressure in said absorber exceeds a predetermined amount.

5. In a refrigerating apparatus of the
 15 kind described, including a still, an absorber, a condenser-receiver, a cooling water tank in which said absorber and receiver are located, a pump for drawing strong liquor from said absorber to said still, a water motor for operating said pump, means conducting the exhaust water from said motor to said cooling water tank, said tank being provided with an overflow, a float in said tank, a main water supply pipe for said motor, a main fuel gas supply pipe for said still, valves in said pipe for controlling the flow therethrough, and means associated with said float adapted to automatically close said valves when the level in said cooling water
 30 tank falls below a certain point.

6. In a refrigerating apparatus of the kind described, in combination with a still, an absorber, a condenser-receiver, an expansion chamber and conduits connecting said
 35 several parts, a valve interposed between said condenser-receiver and said expansion chamber, a receptacle intermediate the absorber and the still for measuring predetermined amounts of absorbent to be transferred from the absorber to the still, and
 40

means for transferring the absorbent in said receptacle to said still at predetermined intervals in timed relation with the operation of said valve.

7. In a refrigerating apparatus of the kind described, in combination with a still, an absorber, a condenser-receiver, an expansion chamber and conduits connecting said several parts, a valve interposed between said condenser-receiver and said expansion chamber, a receptacle intermediate the absorber and the still for measuring predetermined amounts of absorbent to be transferred from the absorber to the still, means for transferring the contents of said receptacle to the still, and means for operating said transfer means and said valve in predetermined timed relation.

8. In a refrigerating apparatus of the kind described, in combination with a still, an absorber, a condenser-receiver, an expansion chamber and conduits connecting said several parts, a valve interposed between said condenser-receiver and said expansion chamber, a measuring transfer device intermediate the absorber and the still for measuring predetermined amounts of absorbent to be transferred from the absorber to the still and for transferring the measured contents to the still, and means for operating said measuring transfer device and said valve in predetermined timed relation.

In testimony that I claim the foregoing as my invention I affix my signature in the presence of two witnesses, this 31st day of December A. D. 1914.

MALCOLM F. EWEN.
